ELHANAN BOWMAN, OF ELMWOOD, ONTARIO, CANADA, ASSIGNOR OF ONE-HALF TO
CHRISTIAN ROTH MILLER, OF BERLIN, ONTARIO, CANADA.

LOCKOUT-TELEPHONE FOR PARTY-LINES.

1,071,292.

Specification of Letters Patent. Patented Aug. 26, 1913.

Application filed February 16, 1912. Serial No. 677,891.

To all whom it may concern:

Be it known that I, ELHANAN BOWMAN, a subject of the King of Great Britain, resident of the village of Elmwood, county 5 of Bruce, Province of Ontario, in the Dominion of Canada, have invented certain new and useful Improvements in Lockout-Telephones for Party-Lines, of which the following is a full, clear, and exact description of same.

The invention relates to improvements in lockout telephones for party lines, as described in the following specification and illustrated in the accompanying drawings 15 that form part of the same.

The invention consists essentially in the novel construction and arrangement of parts, whereby the means for connecting with the main line in all the instruments 20 on the line may be controlled from any one instrument, and whereby the polarization of the armature of the lock-out magnets is rectified automatically on the release of the receiver hook.

25 The objects of the invention are, to insure privacy on party lines preventing a third party cutting in when the line is in use, to increase the efficiency of the instrument rendering it more sensitive in its operation, 30 to economize in battery power, to allow a third party to obtain connection with central in cases of emergency without interrupting the other parties, and to devise a simple and improved mechanism which will 35 not be liable to get out of order.

In the drawings, Figure 1 is a diagrammatic view of a telephone constructed in accordance with my invention showing the door of the casing open and partly broken 40 away. Fig. 2 is an enlarged front elevational view of a portion of the contact making and lock-out mechanism showing the position of the parts in the first contact position following the release of the receiver hook. Fig. 3 is an end elevational view of the magnets, armature and operating rod shown in Fig. 2. Fig. 4 is a top plan view of the mechanism shown in Fig. 2. Fig. 5 is a front elevational view of the 45 contact mechanism shown in Fig. 2 illustrating the position of the parts on the breaking of the first contact. Fig. 6 is a front elevational view of the contact mechanism showing the position of the parts in

the second contact position. Fig. 7 is a 55 front elevational view of the contact mechanism illustrating the position of the parts following the breaking of the second contact when the line is clear. Fig. 8 is a front elevational view of the contact mechanism 60 illustrating the position of the parts following the breaking of the second contact when the line is in use.

Like numerals of reference indicate corresponding parts in each figure.

65 Referring to the drawings, 1 is the telephone having a suitable generator magneto 2, batteries 3, condenser 4, induction coil 5, receiver hook 6 and receiver 7. These several devices are wired and operatively 70 connected together in a manner which will be more fully explained hereinafter, though any explanation of such apparatus will be brief as these parts are all more or less known and common. Certain particular 75 features in the wiring are, however, essential to the present invention. The receiver hook 6 is pivotally supported from the bracket 8 at its inner end and spring actuated to spring upwardly by the leaf 80 spring 9 connected thereto through the link 10.

11 is a spring arm secured at one end to the receiver hook 6.

12 is a rod pivotally secured to the free 85 end of the spring arm 11 and extending upwardly therefrom into a casing 13 arranged within the main casing of the telephone, said arm being supported in a vertical position by a guide 14 rigidly supported within said casing and through which said rod extends and is slidably therein. The upper end of the rod 12 is formed with an angular lateral offset 15 and a perpendicularly arranged crooked portion 16 90 terminating in a straight upper portion 17.

18 is an electro-magnet rigidly supported within the small casing 13.

19 is the armature of the electro-magnet 18 supported upon a flexible spring arm 100 20, said arm being secured at its lower end to a bracket 21 within the casing 13 and said bracket having an adjusting screw 22 threaded therein to adjust the position of the arm 20 and armature 19 in relation to 105 the core of the said magnet.

23 is a light frame secured to the side of the armature 19 away from the electro-

magnet 18, said frame having a bent portion 24 (see particularly Fig. 4) adapted to allow the rod 12 to rise freely and also having the portion 25 adapted to engage the outwardly curved portion of the crooked end of the rod 12.

26 is a downwardly extending V-shaped member forming part with the frame 23 and arranged to the forward side of the upper end of the rod 12. The portion 25 of the frame is so arranged that as the rod 12 is moved upwardly and the straight portion 17 disengages from the rounded contact 27 on the armature 19 the curved portion 16 of the crooked end of the rod engages a rounded contact 28 secured to the inner side of said portion 25, thereby pulling the frame and the armature connected therewith away from the ends of the core of the magnet 18 in the event of there being any tendency for the armature to stick.

29 is an electrical contact member arranged within the casing 13 and electrically connected through the wire 30 to the wire 31 leading to the receiver from the binding post 32 connected to one of the main line wires.

33 is a spring contact arm arranged adjacent to the contact member 29 and adapted to be moved into contact therewith and having a laterally extending loop or hook-shaped portion 34 at its lower end, said hook-shaped portion being adapted on the raising of the rod 12 to engage a projecting block 35 of non-conducting material secured to one side of the said rod and to make an electrical connection with the contact 29. The spring contact 33 is electrically connected through the wire 36 to the electro-magnet 18 and the said electro-magnet is connected through the wires 37 and 38 to the binding post 39 leading to the other line wire.

40 is a spring contact arm arranged adjacent to the contact 33 and extending below the same and having a crooked lower end 41 adapted to be engaged by the block 35 on the rod 12 and to make an electrical connection with the spring arm 33. The contact 40 is electrically connected through the wire 42 with the batteries 3 and when said contact 40 is in contact with the arm 33 an electrical connection through the magnet 18 is established through the wires 36 and 37, the wire 43, spring contacts 44 and 45 and wire 46 to the batteries.

It will be seen that as the rod 12 rises, a momentary connection is made through the latter circuit shunting the battery current through the electro-magnet coils. When this circuit is closed the upper straight end 17 of the rod 12 is holding the armature in contact with the magnet core. The flow of current through the coils of the magnet thus rectifies the polarization of the arma-

ture and renders it very sensitive and easily attracted by the magnet when energized from the outside circuit. As the rod 12 continues its upward movement the temporary electrical connection between the batteries and the magnet 18 is broken by the release of the spring arm 40. Following this temporary connection with the batteries the curved portion 16 of the rod 12 engages the rounded contact 28 and through the frame 23 pulls the armature away from the magnet coils if there is any tendency for the said armature to stick but ordinarily the spring arm 20 carrying the armature draws it away from the magnet core. Following this a temporary connection is established between the main line and the electro-magnet through the operation of the spring arm 33 engaging the contact 29 in the manner described. Coincident with the establishing of the electrical connection between the electro-magnet and the main line the shoulder 47 of the crooked end of the rod 12 engages the contact 27 and moves the armature against the magnet core. In the event of the line being in use, the battery current flowing through the electro-magnet will cause the armature 19 to be held to the core while the contact between the spring contact arms 29 and 33 is maintained.

48 is a spring contact arm electrically connected to the wire 42 leading from the contact arm 40.

49 is an electrical contact supported on the frame 23 and insulated therefrom and electrically connected through the wire 50 to the binding post 39, said contact being adapted to engage the spring contact 48 and to close an electric circuit from the binding post 39 through the wires 42 and 51, spring contacts 52 and 53, wire 54, generator contacts 55 and wires 56 and 57 to the binding post 32.

58 is a branch rod extending laterally from the rod 12 and having an upward extension 59 pointed at the end. The pointed end is so arranged that it extends slightly above the depending apex of the plate 26 secured to the armature 19 just prior to the block 35 releasing the spring arm 33 from contact with the arm 29. If the line is in use, the electro-magnet 18 will be energized and hold the armature to it and the point of the rod 59 will engage the plate 26 to the side of the apex farthest from the magnet thus mechanically holding the armature so that the contacts 48 and 49 cannot come into engagement. If the line is free the armature will be released immediately the shoulder 47 passes over the contact 27 and the spring arm 20 will throw the said armature away from the magnet allowing the point of the rod 59 to engage the side of the plate 26 nearest the magnet and as the rod 12 moves to the limit of its stroke the rod 59

will force the armature over bringing the electrical contacts 48 and 49 into engagement. The rod 12 is supported on the spring arm 11 so that none of the parts will be injured in the event of the point of the rod 59 coming in contact with the apex of the plate 26. It will be seen that the generator circuit is thus connected with the main line and on the turning of the generator 10 crank the circuit is closed. At the same time an electrical connection is made through the wire 42, condenser 4, wires 60 and 61, coil 5, wire 62, plates 63 and 64, wire 65, receiver 7 and wire 31 to the binding post 32. The receiver circuit is thus completed through the condenser which is not a conductor of the direct battery current.

The transmitter circuit is closed simultaneously with the generator circuit through 20 the plate 67 and leaf spring 9 being brought into contact by the raising of the receiver hook, one branch being through the wire 68, coil 5 and wire 69 to the transmitter 70 and the other branch being through the wires 66 25 and 42 to and through the batteries to the wire 71. When a connection to another instrument has been obtained and it is desired to lock-out a third party a button 72 is brought into operation. This button 72 is 30 arranged on the end of a rod 73 secured to a spring contact plate 74, said spring contact plate being connected with the battery through the wire 75.

76 is a spring contact plate arranged close 35 to the plate 74 and adapted to be electrically connected therewith on the button 72 being pressed inward.

77 is a wire connecting the plate 76 with the coil 5.

40 78 is a spring latch projecting from the inner end of the receiver arm 6 and is adapted, when the receiver is off, to engage the contact 74 when the button 72 is pressed inwardly. The latch thus holds the plates 45 74 and 76 in electrical contact thereby closing the circuit from the batteries through the wires 75 and 77 to the coil 5. From the coil 5 the wire 62 leads to the plate 63 and the current flows through the plate 64, wire 50 65 and receiver circuit to the post 32. The return circuit from the post 39 leads through the wire 50 to the contacts 49 and 48 and through the wires 42 to the batteries. This connection is immediately broken on the re- 55 placing of the receiver.

79 is a spring contact arranged adjacent to the spring contact 53 and a wire 80 leads therefrom to the binding post 81 which is grounded.

60 82 is a push button arranged in the side of the instrument and engaging the spring contact 53 and adapted on being pressed inwardly to establish an electrical connection between the plates 53 and 79 thereby connecting the generator circuit to the ground 65

wire so that an emergency call to central can be made in the event of the instrument being locked out from the main line.

83 and 84 are wires electrically connected to the binding posts 32 and 39 and connecting the ringer 85 to the main line.

In the operation of this instrument, a person desiring to use the same operates the generator which is connected to the main line through the wire 56 leading from the binding post 32, the return circuit being through the wire 54, contacts 53 and 52, wires 51 and 42, spring contacts 48 and 49 and wire 50 to binding post 39. The ringer 85 is also connected to the main line through the wires 84, 83 and 57. When the call is made the user lifts the receiver from the hook and the said hook being spring actuated to rise, moves the rod 12 upwardly. The block 35 on the rod 12 first engages the crook of the spring arm 40, pressing said arm into electrical contact with the arm 33 thereby closing the local battery circuit through the electro-magnet 18 in the manner described, the upper end of the rod simultaneously engaging the armature 19 and moving it into contact with the magnet core. The polarization of the magnet core is thus corrected and the magnet coils rendered more sensitive. As the rod 12 moves upwardly 95 the armature is drawn away from the magnet by the crook 16 and the block 35 disengages from the crooked contact 40. The further movement of the rod brings the shoulder 47 of the said rod into engagement 100 with the armature 19 returning it into contact with the magnet core and the block 35 presses against the crooked end of the spring contact 33 to make an electrical connection with the contact 29. The electro-magnet is 105 thus connected to the main line as hereinbefore described and if the line is in use, the battery current from the other instruments flows through the electro-magnet 18 and holds the armature until the point of the 110 branch rod 59 engages the plate 26, the rod holding said armature in the manner described. If the line is free the spring 20 will move the armature away from the electro-magnet and the branch rod 59 will connect the several circuits to the main line as 115 described. When the main line connection has been obtained and the desired party obtained, the battery circuit may be connected in by pressing in the button 72, thereby energizing the line so that all other instruments on the line will be effectually locked out by the operation of the apparatus described. An emergency call may however be made at any time by operating the button 82 120 obtaining a ground circuit connection with central.

A very important feature in this invention is that by the peculiar arrangement of wiring with the spring contacts 63 and 64 130

and the condenser and the contacts 44 and 45, several electrical connections are made with a single set of batteries utilized simultaneously in two separate circuits, that is to say, the batteries are utilized in the transmitter circuit and also connected with the main line by means of the button 72 and contacts 74 and 76 to lock out other telephones and insure privacy.

- 10 If the person using the instrument does not desire to lock out the other instruments on the line the button 72 is not operated. The transmitter circuit, constituting wire 71, batteries 3, wires 42 and 66; contacts 67 and 9, wire 68, coil 5, and wire 69, is connected to the receiver circuit of the other instrument through the wire 42, contacts 48 and 49 and wire 50 connected to one line wire and enters the other instrument on the wire 31 completing the circuit through the wire 65, contacts 64 and 63, wires 62 and 61, condenser 4, wire 42 and succeeding connections back to the first instrument. The electrical connection is thus established but as the 25 battery current will not pass through the condenser there will be no flow of battery current over the line. In the event of the button 72 being pushed in, the battery current will flow through the wire 77, contacts 30 76 and 74 and wires 75, 71, 69, 68, contacts 9 and 67 and wire 66 to wire 42 thus bridging the condenser and allowing the flow of the battery current over the main line so that if a third party endeavors to cut in on 35 the line, the magnet 18 will be energized and prevent their obtaining a connection in the manner described. This arrangement of contacts and wiring allows the use of one set of batteries for two purposes, that is, for 40 the operation of the transmitter and for the lock out function, and both may be utilized at the same time without interfering with the proper operation of the instrument.

Another important feature is that by the 45 use of the push button 82 an emergency call to central may be made through the ground connection by a locked out party and central may then cut in on the line and if necessary release the third party's phone by 50 connecting a counteracting battery current on to the main circuit to neutralize the magnets 18 and allow the third party to get connection with the main line and ring up the party desired. An additional connection is 55 also provided in a button 86 connected by a wire 87 to the wire 42. This button on being pressed in makes a connection to the ground through the contact 79, wire 80 and post 81 and enables subscribers using the instrument 60 in the event of the line wires being bridged or one of them being broken.

What I claim as my invention is:

1. In a lockout telephone for party lines, the combination with the main line wires, 65 of an electro-magnet, a local battery circuit,

a transmitter circuit, a receiver circuit, an armature for said electro-magnet carrying an electric contact adapted to close the receiver and transmitter circuits to the main line, a receiver hook, and means operated by the receiver hook adapted to first momentarily close the local battery circuit through said electro-magnet to polarize the armature, then momentarily connect the electro-magnet to the main line circuit and finally 75 to move said armature to close the transmitter and receiver circuits to the main line or hold said armature to maintain an open receiver circuit.

2. In a lockout telephone for party lines, 80 the combination with the main line wires, of an electro-magnet, an armature supporting a movable electric contact which is electrically connected to one of the main line wires and is adapted to close the transmitter and receiver circuit to the main line, a local battery, a receiver hook, means operated by said receiver hook adapted to first electrically connect said electro-magnet with said local battery momentarily coincidently moving said armature into engagement with the magnet core, then breaking said connection with the local battery and momentarily connecting said magnet with the main line and finally moving the armature and contact 95 carried thereby to close connection with the main line or to retain an open circuit.

3. In a lockout telephone for party lines, the combination with the main line wires, of an electro-magnet, a local battery circuit, a 100 transmitter circuit, a receiver circuit, an armature for said electro-magnet carrying an electric contact adapted to close the receiver and transmitter circuits to the main line, a receiver hook, means operated by the receiver hook adapted to first momentarily close the local battery circuit through said electro-magnet to polarize the armature, then momentarily connect the electro-magnet to the main line circuit and finally to 110 move said armature to close the transmitter and receiver circuits to the main line or hold said armature to maintain an open receiver circuit, and means for electrically connecting the local battery circuit on to the main line to energize the electro-magnets in the other instruments on said main line.

4. In a lockout telephone for party lines, the combination with the main line wires, of an electro-magnet electrically connected with 120 one of said main line wires, a local battery, a movable contact electrically connected with said battery, a movable contact electrically connected with said magnet and adapted to be engaged by the first movable contact to close the battery circuit through said magnet, a stationary electric contact electrically connected to the return main line wire and adapted to be engaged by the second movable electric contact to close the main 130

- line circuit through said electro-magnet, transmitter and receiver circuits, an armature arranged adjacent to said electro-magnet, a stationary contact adapted to be electrically connected to said transmitter and receiver circuits, an electric contact carried on said armature and electrically connected with one of the main line wires and adapted to engage the stationary contact electrically
- 5 connected to one of said transmitter and receiver circuits, a receiver hook, and means operatively connected to said receiver hook adapted to first bring the first two movable contacts together momentarily to close the
- 10 battery circuit through the magnets and to simultaneously move the armature into contact with the magnet core to polarize the same, then to break the contact of said movable contacts and move the armature away
- 15 from the magnet core, then to move the second movable contact to engage the stationary contact connected with the main line closing the magnet circuit on to the main line, and simultaneously moving the armature into engagement with the magnet core, then breaking the electric contact between said movable and stationary contacts, and finally engaging the armature to hold it in contact with said magnet core or to move it
- 20 so as to bring the electric contact carried thereby into engagement with the stationary contact connected to the transmitter and receiver circuits to close said circuits to the main line.
- 25 5. In a lockout telephone for party lines, the combination with the main line wires, of a local battery circuit, transmitter and receiver circuits, an electro-magnet, an armature carrying an electric contact adapted to
- 30 close the transmitter and receiver circuits to the main line, a V-shaped guide carried by said armature, a receiver hook, means operated by said receiver hook adapted to momentarily close the local battery circuit to
- 35 the magnet then to the main line, and a member connected to said receiver hook adapted to extend to either side of the apex of said guide to hold the contact member carried by said armature positively in or out
- 40 of contact with the main line.
- 45 6. In a lockout telephone for party lines, the combination with the main line wires, of a generator circuit having one lead connected with one of said main line wires, a
- 50 stationary electric contact member connected to the other lead, a battery circuit having one lead connected to one of said main lines and the other lead connected to said stationary contact, an electro-magnet, an armature
- 55 for said electro-magnet, an electric contact carried by said armature and electrically connected with one of said main line wires and adapted to engage said stationary contact to connect the generator and battery circuits to the main line, a receiver hook, means

carried by said receiver hook for controlling the movement of said armature and the contact carried thereby to close the circuits to the main line or to positively prevent the connection to the main line, a circuit breaking device arranged in said battery circuit, a push button adapted to close said circuit breaker, and means carried by said receiver hook for holding said circuit breaker closed when said hook is raised and the instrument is in use.

7. In a lockout telephone for party lines, the combination with the main line wires, of an electro-magnet, a local battery circuit, a transmitter circuit, a receiver circuit, an armature for said electro-magnet carrying an electric contact adapted to close the receiver and transmitter circuits to the main line, a receiver hook, means operated by the receiver hook adapted to first momentarily close the local battery circuit through said electro-magnet to polarize the armature, then momentarily connect the electro-magnet to the main line circuit and finally to move said armature to close the transmitter and receiver circuits to the main line or hold said armature to maintain an open receiver circuit, a pair of spring contact plates normally held apart arranged one in electrical contact with the main line and the other in electrical contact with the battery circuit, a push button adapted to close said contacts together to throw the battery current on the main line, and a spring hook carried by said receiver hook adapted to engage and hold said contacts together following the operation of the push button of the receiver hook if first raised said spring hook being adapted to release said contacts when the receiver hook is depressed.

8. In a lockout telephone for party lines, the combination with the main line wires, of a local battery circuit in the instrument, a generator circuit adapted to be connected with said main lines, an electro-magnet arranged in said local battery circuit, an armature movably supported adjacent to said electromagnet, means controlled by the movement of said armature for opening or closing said generator circuit, a receiver hook, means operated by said receiver hook for moving said armature, and a plurality of spring contact members adapted to be operated successively by the movement of said receiver hook to momentarily close the local battery circuit through said magnet and to momentarily close the main line circuit through said magnet following the breaking of the local circuit.

9. In a lockout telephone for party lines, the combination with the main line wires, of a local battery circuit in the instrument, a generator circuit connected with said main lines, an electro-magnet arranged in said local battery circuit, an armature movably

supported adjacent to said electro-magnet, means controlled by the movement of said armature for opening or closing said generator circuit, a pair of spring contact arms arranged in said local battery circuit and normally held apart, a receiver hook, and means operated by the movement of said receiver hook for moving said armature into contact with the core of said magnet, and 5 means operated by said receiver hook for moving said spring arms into contact to close the local battery circuit momentarily to energize said magnet and polarize said armature.

10 10. In a lockout telephone for party lines, the combination with the main line wires, of a generator circuit, a receiver circuit, and a battery circuit all connected to said main line and having one lead connected to a common contact member, a local battery circuit, a pair of spring contact arms arranged in said local battery circuit and having crooked ends, a contact member connected to a branch from the receiver circuit and 15 adapted to co-act with one of the aforesaid spring arms, an electro-magnet arranged in said local circuit and having a branch connection to the receiver circuit, a spring arm, an armature supported on said spring arm 20 an open guide frame secured to said armature, an electrical contact carried on said frame and adapted to engage said common contact member to close the circuits leading thereto with the main line, a receiver hook, 25 a rod operatively connected to said receiver hook and slidably held mid-way of its length, said rod having a crooked upper end adapted to extend through said guide frame, the extreme upper end of said crook 30 being adapted to engage the armature and move it into contact with the magnet core on the initial upward movement, the center portion of said crook being adapted to engage the guide frame and draw the armature away from the magnet and the lower 35 end of said crook being adapted to engage the armature and return it to engage the magnet, each portion acting successively, a projection secured to said rod intermediate 40 of its length and adapted to engage the lowermost crooked spring contact arm to bring it into electrical contact with the other crooked arm to close the local battery circuit 45 through the magnet at the period when the armature is first moved into contact with the core, said projection being adapted to release the first crooked spring arm and as the rod moves upwardly engaging the second crooked arm moving it into electrical 50 contact with the contact connected to the branch from the receiver circuit and closing the receiver circuit through the magnet following the withdrawal of the armature and concurrent with the return movement there- 55 of caused by the engagement of the lower

part of the crooked end of said rod, and means carried by said rod adapted to engage a portion of said frame before the second crooked spring contact is released and to hold said armature and frame positively so that the electric contact carried by said frame is either in or out of contact with the electric contact common to the several outside circuits.

70 11. In a lockout telephone for party lines, the combination with the main line wires, of a receiver having one lead directly connected to one of said main wires, a spring contact connected to the other lead from said receiver, a spring contact adapted to co-act with the aforesaid contact, a receiver hook operatively connected to move said contacts into engagement, a condenser electrically connected to the latter spring contact, a contact electrically connected to said condenser, 75 means actuated by said receiver hook for electrically connecting the latter contact with the other main line, a transmitter, a battery circuit connected with said transmitter, and means operated by said receiver hook for connecting said transmitter circuit with the receiver circuits in the other instruments on the line.

80 12. In a lockout telephone for party lines, the combination with the main line wires, 90 of a receiver, a condenser wired to said receiver, a receiver hook, means operated by said receiver hook for closing the receiver circuit through said main lines, a transmitter, a battery circuit connected to said transmitter, means arranged in said transmitter circuit and operated by said receiver hook adapted to electrically connect said transmitter circuit with the main line concurrently with the closing of the receiver circuit, and means for connecting said battery circuit direct to the main line.

95 13. In a telephone, the combination with the main line wires and receiver and transmitter circuits, of a ground connection, a contact connected to said ground connection and a push button electrically connected with the receiver and transmitter circuits and adapted to engage said contact to close a connection through the ground to complete a circuit in the event of one of the main line wires being broken or said main wires being bridged.

100 14. In a lockout telephone for party lines, in combination, a pair of main line wires, a generator circuit, a receiver hook, means controlled by the movement of the receiver hook for connecting the generator circuit to the main lines, a receiver having one terminal connected to one main line, a spring contact electrically connected to the other receiver terminal, a spring contact actuated by the upward movement of the receiver hook to close contact with the other spring contact, an induction coil and a condenser. 105 110 115 120 125 130

wired to the latter contact, means actuated by the receiver hook adapted to close the receiver circuit to the other main line, a battery a transmitter, a pair of electrical contacts operated by the receiver hook, wired to said transmitter and said battery and closed on the raising of the receiver hook, an electro-magnet, an armature for said magnet controlling the connection of the transmitter and receiver circuits with the main line, an electric circuit through said electro-magnet connected to the local batteries, a pair of electric contacts arranged in

the battery circuit to said magnet and normally held closed while the receiver hook is down, and a pair of electrical contacts in said local battery circuit actuated by the first initial movement of the receiver hook to close the said circuit momentarily.

Signed at the town of Chesley this twenty fifth day of January 1912.

ELHANAN BOWMAN.
